ABSTRACT OF THE DISCLOSURE

Apparatus for use with rotary regenerative heat exchangers having sector plates and axial sealing means which provides for sudden thermal deformations of the rotor which can cause jamming between the adjacent surfaces of the rotor, the sealing means and the sector plates by providing a single yielding connection interconnecting the sector plates and the adjacent sealing means at each end of the rotor which transmits motion between the sector plates and the adjacent sealing means so that the movement of the latter in response to a deformation brings about a corresponding movement of the former, thus avoiding contact between the two.

The present invention relates to a regenerative heat exchanger of the type which comprises a stationary housing in which is provided a cylindrical rotor containing a regenerative mass. The housing includes ducts for the heat exchanging fluids and these ducts have openings at either end of the rotor for directing separate flows of fluid through the regenerative mass. In order to prevent mingling of the fluid flows there are provided sealing means between the rotor and the housing which include swingable sector plates hinged at their radial inner ends to the stationary housing and located in sealing proximity to the end surfaces of the rotor for separating adjacent duct openings, each sector plate at one end of the rotor being axially aligned with a sector plate at the opposite end. Further there are provided axial sealing means extending between aligned sector plates and cooperating with the outer cylindrical rotor surface.

In heat exchangers of this type the rotor is subject to thermal deformation during operation due to non-uniform temperature distribution. For the same reason also the housing is deformed to a certain degree. In normal operation the swingable sector plates adapt themselves to the dished form of the rotor and the axial sealing means may be adjusted to occupy the correct position relatively to the outer rotor surface.

Under certain conditions such as at start and over-load the deformations may be so large as to cause jamming of the rotor due to contact between the rotor and the sector plates and axial sealing means respectively. The sector plates and the axial sealing means are actuated by means yieldingly forcing them towards stop members determining their operative positions. In this manner jamming of the rotor is prevented as the sector plates and/or the axial sealing means move away against the action of the yielding force when they come into contact with the rotor so that this contact only results in a certain braking of the rotor but not in a total stand-still. This braking action in turn results in a greater power demand indicated by a suitable instrument or alarm device so that the positions of the sector plates and/or the axial sealing means may be manually adjusted.

According to the invention there are provided motion transmitting means interconnecting the sector plates and the axial sealing means such that an increase of the distance between the outer ends of aligned sector plates re-

2

sults in a radial outward movement of the adjacent axial sealing means. Thanks to this connection it is possible to use a single common means for producing the yielding force acting upon the sector plates and the axial sealing means. Further, if for instance the conditions are such that due to the thermal deformation of the rotor its cylindrical surface comes in contact with the axial sealing means and moves it outwardly the sector plates are somewhat separated so that they do not come in contact with the end surfaces of the rotor. Under other conditions the deformation of the rotor may cause separation of the sector plates in which case the axial sealing means is moved outwardly so that it does not come in contact with the rotor. It is evident that in this manner the rotor will be braked either by the axial sealing means or by the sector plates but practically never by the axial sealing means and the sector plates at the same time.

In the accompanying drawing there is shown a perspective view of a part of regenerative heat exchanger according to the present invention.

The drawing illustrates the invention as applied to a heat exchanger of the type shown in our U.S. Patent No. 3,250,316, granted May 10, 1966 and more particularly to such a heat exchanger provided with a device according to FIG. 14 of said patent application.

Referring to the drawing reference numeral 10 indicates a cylindrical rotor which is divided into sectorial compartments by partitions 12. The rotor 10 is rotatably mounted in a housing 14 which is provided with ducts for the heat exchanging fluids parts of which are shown in broken lines in the drawing at 16 and 18.

In circumferential direction the openings of the ducts 16 and 18 are in known manner separated by sector-shaped plates two sector plates being provided at each end of the rotor and each sector plate at one end of the rotor being in axial alignment with a sector plate at the other end of the rotor. In the drawing there are shown two axially aligned sector plates viz. an upper sector plate 20 and a lower sector plate 22. At their radially inner ends the sector plates 20 and 22 are hinged to stationary center plates (not shown) so that they are swingable in an axial plane.

A rod 24 is secured to the lower sector plate 22 and extends upwardly through a tubular member 26 secured to the upper sector plate 20 and passing freely through a stationary casing end wall 28. On a threaded portion of the rod 24 there is provided at the under side of the sector plate 20 a nut (not shown) which serves as an adjustable stop member determining the minimum distance between the ends of the sector plates 20 and 22.

A link 30 is pivotally connected to the housing end wall 28 and supports a lever 32 one arm of said lever 32 carrying a weight 34. The other arm of the lever 32 is pivotally connected to a suspension lever 36 which is provided with a plurality of holes for the suspension of the rod 24. In the example illustrated the upper end of the rod 24 is connected to a hole located vertically below the pivotal connection between the lever 32 and the suspension lever 36.

One end of the suspension lever 36 is inserted between an eccentric 38 and a stop member 40 carried by a bracket 42 secured to the tubular member 26. The eccentric 38 and the stop member 40 are located such that they prevent counterclockwise swinging of the suspension lever 36 from the position shown.

To each sector plate is secured a radially outwardly extending bar 44 on to which is threaded a tube 46. Each tube 46 carries a yoke member 48 the ends of which are connected to a frame-like link element 50 which in turn is connected to an axially extending sealing member 52 cooperating with the outer cylindrical surface of the rotor

10. The link elements 50 form an angle of about 45° with the axis of rotation and converge towards this axis.

The ends of the bars 44 and the tubes 46 protrude through holes in the housing 14 which holes are such as to permit a certain axial movement of the bars and the tubes. Each tube end is threaded and carries a nut 54 which is rotatably connected to the end of the bar 44. It is evident that turning of the nut 54 will result in a radial movement of the yoke 48.

The holes in the housing 14 are surrounded by bellows-like seals 56.

Each link element 50 carries an axially directed lever member 58. At the free end of one of the lever members 58 there is provided a pin 60 which engages a slot 62 at the end of the other lever member 58. The levers 58 form a coupling means between the link elements 50 so that these elements swing substantially synchronously in opposite directions.

The axial sealing member 52 is substantially U-shaped in cross section and its substantially radial side-portions cooperate with radial walls 64 secured to the inside of the housing 14 in order to prevent mingling of the fluid flows in the space between the rotor 10 and the housing 14.

The weight 34 forms a counter-weight which counter-balances the weight of the sector plates 20 and 22, the axial sealing means 52 and all parts carried by these elements. Therefore, a very little force is required to swing the whole system so that a normal deformation of the rotor is possible without any risk of harmful contact pressure between the rotor and the sector plates and axial sealing means respectively. However, the counter-weight 34 also produces a force biasing the sector plates towards each other and towards the position determined by the above-mentioned stop member provided on the rod 24. Due to the link elements 50 this stop member also determines the position of the axial sealing member 52.

It is evident that a radial outward movement of the axial sealing member 52 will be yieldingly counter-acted by the force exerted by the counter-weight 34 and the movement will take place under a simultaneous separation of the sector plates 20 and 22. Correspondingly a separation of the sector plates 20 and 22 will be yieldingly counter-acted by the counter-weight 34 and will take place under a simultaneous radial outward movement of the axial sealing member 52.

By means of the nuts 54 the position of the axial sealing member 52 may be adjusted such that there is always a desired small clearance of uniform width also when the outer surface of the rotor becomes slightly conical. By turning one of the nuts 54 it is possible to vary the inclination of the sealing member 52 and by turning both nuts 54 the radial position of the member 52 is varied. These adjustments do not affect the sector plates 20 and 22. However, if the sealing member 52 is subjected to a radially outwardly directed force it moves outwardly in the same manner irrespective of the position of the point where the force is applied and this movement results in a separation of the sector plates. Due to the coupling means formed by the lever members 58 a radial movement of the upper end of the sealing member 52 is always accompanied by a corresponding movement of the lower end thereof.

Due to the fact that the link elements 50 form an angle of about 45° with the axis of the rotor the force opposing outward movement of the sealing member 52 will be substantially the same as the force opposing separation of the sector plates 20 and 22.

In order to permit manual separation of the sector plates 20 and 22 and a corresponding retraction of the axial sealing member 52 the eccentric 38 is provided with a handle 39 by means of which the eccentric 38 can be turned such that the suspension lever 36 is swung clockwise whereby the sector plates are separated.

The housing 14 is provided with suitable openings through which the stop members on the rods 24 are accessible for adjustment.

By selecting different holes of the suspension lever 36 for the connection of the rod 24 it is possible to vary the force exerted by the counter-weight 34 and biasing the sector plates towards each other and the sealing member 52 towards the rotor.

The invention is not limited to embodiments of heat exchangers in which the force biasing the sealing elements towards their operative positions are produced by weights but may be applied also to such exchangers in which the said biasing force is exerted by springs.

I claim:

1. A regenerative heat exchanger comprising a stationary housing, a cylindrical rotor provided in said housing and containing a regenerative mass, said housing including ducts for the heat exchanging fluids and said ducts having openings at either end of said rotor for directing separate flows of fluid through said regenerative mass, sealing means between said rotor and said housing for preventing mingling of the fluid flows, said sealing means including swingable sector plates hinged at their radially inner ends to the stationary housing and located in sealing proximity to the end surfaces of the rotor for separating adjacent duct openings, each sector plate at one end of the rotor being axially aligned with a sector plate at the opposite end, and axial sealing means extending between aligned sector plates and cooperating with the outer cylindrical rotor surface, and motion transmitting means interconnecting said sector plates and said axial sealing means such that an increase of the distance between the outer ends of aligned sector plates results in a radial outward movement of the adjacent axial sealing means.

2. A heat exchanger as defined in claim 1 in which said motion transmitting means consists of a linkage comprising link members connecting each sector plate with the adjacent axial sealing means, said link members being swingable in substantially axial planes and converging towards the axis of rotation.

3. A heat exchanger as defined in claim 2 in which said linkage comprises adjustable articulation points.

4. A heat exchanger as defined in claim 3 in which the connection points of said links to said sector plates are radially adjustable.

5. A heat exchanger as defined in claim 2 and further comprising coupling means operatively interconnecting corresponding links at either end of the rotor such as to make these links swing substantially synchronously in opposite directions.

6. A heat exchanger as defined in claim 5 in which said coupling means includes two lever members each being rigidly secured at one end to one of the links to swing therewith, the free ends of said lever members being pivotably and slidably connected in order to transmit swinging motion from one link to the other.

7. A heat exchanger as defined in claim 1 and further comprising means yieldingly forcing said sector plates towards each other and a stop member determining the smallest distance between the outer ends of said sector plates.

8. A heat exchanger as defined in claim 2 wherein each link forms an angle of about 45° with the axis of rotation in the normal working position of the sector plates and axial sealing means.

9. A heat exchanger as defined in claim 7 comprising means for manual separation of said sector plates.

10. A heat exchanger as defined in claim 7 comprising means interconnecting the outer ends of said axially aligned sector plates, said means comprising a lever system including a suspension lever, a first element carried by the upper one of said sector plates and a second element carried by the lower one of said sector plates, said two elements being attached to two horizontally spaced

points on said suspension lever, a substantially horizontal double arm lever swingably mounted on a stationary support, a counter-weight secured to one arm of said double-armed lever, the other arm of said double-armed lever being pivotally connected to said suspension lever such as to exert a force on said suspension lever tending to move said sector plates towards each other while said counter-weight counterbalances the weight of the sector plates and associated movable parts.
